US00D621629S

(12) United States Design Patent
Weimer et al.

(10) Patent No.: US D621,629 S
(45) Date of Patent: * Aug. 17, 2010

(54) TABLE FRAME

(75) Inventors: Kent Weimer, Columbia City, IN (US);
Douglas Garofalo, Chicago, IL (US);
Grant Gibson, Chicago, IL (US)

(73) Assignee: Wabash Valley Mfg., Inc., Silver Lake, IN (US)

() Term: 14 Years

(21) Appl. No.: 29/316,052

(22) Filed: Aug. 19, 2009

(51) LOC (9) Cl. 06-01

(52) U.S. Cl. D6/337

(58) Field of Classification Search D6/330,
D6/335-338, 340, 349-355, 358, 359, 364,
D6/366, 376, 491, 495, 500-502; 297/16.1,
297/39, 46, 135, 140, 156, 158.3, 158.4,
297/175, 177, 187, 195.1, 195.11, 211, 245,
